UNITED STATES PATENT OFFICE.

JOSEPH J. WALSER, OF CHICAGO, ILLINOIS, ASSIGNOR TO GOSS PRINTING PRESS COMPANY, A CORPORATION OF ILLINOIS.

OFFSET MECHANISM FOR PRINTING-PRESSES.

1,331,733.

Specification of Letters Patent.

Patented Feb. 24, 1920.

Application filed June 18, 1917. Serial No. 175,409.

To all whom it may concern:

Be it known that I, JOSEPH J. WALSER, a citizen of the United States, residing at Chicago, county of Cook, and State of Illinois, have invented certain new and useful Improvements in Offset Mechanism for Printing-Presses, of which the following is a specification.

The invention relates to rotary perfecting printing presses, and more especially to offset methods, and to offset devices coöperating with the second impression cylinder, to prevent offset from, and smutting of, the previously printed side of the web.

Objects and advantages of the invention will be set forth in part hereinafter and in part will be obvious herefrom, or may be ascertained by practice with the invention, such objects and advantages being realized and attained through the means, instrumentalities, and combinations pointed out in the appended claims.

The invention consists in the novel parts, constructions, arrangements, combinations and improvements herein shown and described.

The accompanying drawings, referred to herein and forming a part hereof, illustrate one embodiment of the invention, and together with the description serve to explain the principles thereof.

Of the drawings:

Figure 1 is a view in elevation, largely diagrammatic, of a device constructed in accordance with the principles of the invention; and

Fig. 2 is a similar view of a somewhat different form of mechanism constructed in accordance with the principles of the invention.

In running a freshly printed web from the first printing couple of a perfecting press into the second printing couple of the press to be perfected thereby, the freshly printed side of the web is against the surface of the impression cylinder as the web passes thereabout and through the impression of the second printing couple. It is essential especially in the better grades of printing, to provide devices designed to prevent the offset of the fresh ink upon the surface of the impression cylinder, and also thereby avoiding or obviating the resultant

smutting or soiling of the web in turn from the surface of the impression.

Heretofore it has been customary to employ for this purpose an offset web, which is run between the freshly printed side of the web and the surface of the impression cylinder, or to employ a shifting tympan sheet on the impression cylinder; or to use an oil offset device whereby an exceedingly thin film of oil is applied to the surface of the impression cylinder, sufficient to prevent, in greater or less degree, the offsetting from the freshly printed web onto the surface of the impression cylinder, while not being sufficient on the other hand to soil the freshly printed web. In certain cases, an oil offset device has been employed in connection with one or the other of the other kinds of offset devices just described.

Certain disadvantages are inherent in the employment of the various offset devices heretofore known. In commercial work a certain amount of ink is more or less gradually deposited on the "packing" or blanket or other surface of the impression cylinder, and there is more or less giving off of paper dust, which mixes with the given-off ink, and these gradually cake or dry on the surface of the cylinder. This dirt, consisting in part of dry ink and of paper dust, becomes intermixed with the oil, and renders the latter dirty, and in the present systems or mechanisms this dirt is again carried back and deposited upon the impression cylinder, and thus the web is smutted and soiled to a greater or less degree. When an offset web is used or a shifting tympan sheet, the offset paper picks up the ink and the paper dust and these gradually become matted or pressed into the paper, thereby soiling the printed web and to some extent causing deterioration in the impression. Also thereby the offset web is made much thicker than when clean and fresh and the offset roll becomes very much larger, which in itself is a great inconvenience, especially when the space allotted thereto in the press is limited.

An object of the present invention is to eliminate or obviate the gathering of ink on the packing or other surface of the offset cylinder, and to prevent the old oil and dirt being carried back to the source of oil sup-

ply and deposited therein, and to provide means for gathering the mixed oil ink and paper dust from the surface of the impression cylinder and for depositing it in a receptacle whereby it will be prevented from contaminating the oil supplied to and used in the offset devices.

Referring to the accompanying drawings, illustrating by way of example an embodiment of the invention, and referring more particularly to Fig. 1, an oil fountain 1 is provided with a fountain roller 2 of the usual type, which roller is rotated either continuously or intermittently as desired. A blade 3 co-operates with roller 2, thereby permitting only a very thin film of oil to pass on the surface of the roller 2 and to be taken therefrom by the feed roller 4.

The roller 4 is oscillated between the fountain roller 2 and an intermediate roller 5, preferably of metal, or other material having a hard, smooth surface. The roller 4 is mounted upon a pair of arms 6, fixed on a shaft 7, the shaft being oscillated by a suitable mechanism (not shown). Co-operating with the roller 5, and in contact therewith, is a roller 8, which conveys the thin film of oil from the roller 5 and deposits it upon the surface of the impression cylinder 9, with which cylinder the roller 8 runs in contact.

The surface of the roller 8 is preferably covered with fabric, which is more or less yielding and absorbent, and such roller is usually covered with carpet. The roller 8 is geared to run preferably at the surface speed of the impression cylinder, or it can be run a little slower or a little faster if desired. This roller lays an exceedingly thin film of oil on the surface of the impression cylinder 9. The web α runs about the impression cylinder 9 with its previously printed side in contact with the surface of the cylinder. As the web α runs between the impression cylinder 9 and the form cylinder 10 the second side of the web is printed.

Co-operating with the impression cylinder 9 and running in contact with the surface thereof beyond the point of emergence of the web α (Fig. 1) is a roller 11, provided with a surface which has more or less of an absorbing and carrying capacity. This roller 11 is run preferably at a different speed from the surface speed of the impression cylinder 9, either faster or slower and in many cases a speed of about three-quarters the surface speed of the impression cylinder 9 will be found effective. The roller 11 runs also in contact with the intermediate roller 5, already described.

Running also in contact with the roller 5 is a conveying roller 12, the roller 12 also running in contact with a roller 13 which latter roller runs in a dirty oil receptacle 14.

65 A scraper 15 acts against the surface of the

roller 13 to clean it and to cause any dirt adherent upon the surface of the roller to be deposited in the oil in the fountain 14. Suitable means for draining and cleaning the fountain 14 may be provided, such as 70 one or more screw taps 16.

Cylinder 33 is a form cylinder adapted to print on the same side of the web with cylinder 10, and cylinder 34 bears the same relation to cylinder 32. By this construction 75 and arrangement, a single small size impression cylinder co-operates with two form cylinders to print the second side of a perfected web, the impression cylinder preventing offset and removing all dirt without the 80 necessity of running an offset web.

The operation of the mechanism just described is substantially as follows:—

The oil from the fountain 1 is carried about the roller 2 in an exceedingly thin 85 layer, and the oscillating feed roller 4 carries the oil from the roller 2 to the hard and smooth roller 5, and deposits it thereon in a thin layer. The oil is taken from the roller 5 by the roller 8, by which roller 90 it is deposited on the surface of the offset cylinder, being deposited thereon in very minute quantities, but sufficient to prevent appreciable offset from the freshly printed side of the web α , and at the same time not 95 defacing the web with the oil.

By reason of the roller 8 taking the oil from the surface of the roller 5, there is no oil deposited from the roller 5 upon the roller 11. The roller 11, it will be remembered, travels in contact with the surface of the impression cylinder 9 beyond the point of emergence of the printed web and ahead of the place of application of the clean oil by roller 8. Roller 11 thus engages with 105 the surface of the cylinder 9 at a place where it carries any loose ink and paper dust, or other dirt, from the web, and any surplus oil which may be intermixed therewith. By reason of the difference in speed between the 110 roller 11 and the impression cylinder 9, and because of the nature of the surface of the roller 11, and by reason of its being dry, it will act as a wiper or cleaner for the surface of the impression cylinder 9. Thus 115 any ink, dust and oil from the portion c of the surface of the impression cylinder 9 is picked up by the roller 11, leaving the surface of the impression cylinder clean and dry.

The oil and dirt are then conveyed to that portion of the surface of the roller 5 which is marked b and is taken therefrom by the roller 12, and is in turn deposited by the roller 12 upon the surface of the roller 13. 125 As the roller 13 revolves, the scraper 15 removes all the dirt or oil from the surface thereof, prevents its being carried back to the roller 12, and causes it to be deposited in the oil in the receptacle 14.

It will be understood that the part *a* of the surface of the rotating roller 5 carries a film of oil, very thin and minute, to the roller 8 which deposits it upon the surface 5 of the impression cylinder 9. The part *d* of the surface of the rotating roller 5 is dry as it comes into contact with the portion, *e* of the surface of the rotating roller 11, which carries the waste oil and the dirt from 10 the portion *c* of the surface of the impression cylinder 9.

The dry surface *d* of the roller 5 takes the waste oil and the dirt, which is carried along the part *b* of the surface of the rotating roller 5, and is deposited upon the part *f* of the surface of the rotating roller 12, leaving the portion *g* of the surface of roller 5 to come back dry and clean to receive a deposition of clean oil from the roller 2, to 20 be conveyed forward and to be deposited upon the surface of the impression cylinder 9.

In Fig. 2 of the drawings, is shown another form of mechanism of somewhat simpler construction which will be found sufficient in some cases. An oil fountain 20 is provided with a roller 21, and with a blade 22 coöperating with roller 21 to insure only a thin film of oil passing about the roller 21. 25 A feed roller 23 is mounted upon arms 24, which arms are fixed to a shaft 25, said shaft being oscillated in a suitable manner. The roller 23 deposits the thin film of oil upon the surface of the roller 26, which is 30 preferably of hard and smooth material, such as metal.

Coöperating with the roller 26, and running in contact therewith is a roller 27, said roller 27 also running in contact with the 40 impression cylinder 28. The roller 27, like roller 8, has a surface preferably of more or less absorbent material, such as carpet, or other suitable fabric. Also running in contact with the roller 27 is a roller 29, running 45 in a dirty oil receptacle 30, there being a scraper or cleaning blade 31 in contact with the face of the roller 29 to remove the dirt and oil from the roller and to effect its deposit in the receptacle. The form roller 32 50 prints the second side of the web *x*.

In this form of device, the thin film of oil from the roller 21 is deposited upon the roller 26, and is carried about on the portion *h* of the surface of said roller 26. The 55 oil is deposited upon the portion *i* of the roller 27 and from there is deposited upon the portion *k* of the surface of the impression cylinder, which is clean and free from ink, dust and oil. In this form the portion 60 *l* of the surface of impression cylinder 28, upon which is the ink, dust or oil left after the emergence of the now perfected web *x* is acted upon by roller 27, which takes up the dust and oil and carries it along the portion *m* thereof and deposits it upon the por-

tion *n* of the roller 29. The scraper 31 70 cleans and dries the surface of the roller 29 as it approaches the point of contact with roller 27, thereby presenting a dry and clean surface thereto to carry away any oil and dirt deposited.

The form of mechanism just described is not in certain cases as efficient as the one first described, but will be found useful and satisfactory where space is limited.

The invention in its broader aspects is not limited to the particular details shown and described, but departures may be made therefrom without departing from the principles of the invention and without sacrificing its chief advantages.

It will be understood that the term "oil" as used herein may apply to any kind of offset fluid, so far as concerns many features of the invention.

What I claim as my invention and desire to secure by Letters Patent is as follows:

1. A printing press having an offset mechanism coöperating with an impression cylinder and including in combination oil applying and oil removing rollers engaging the impression cylinder closely contiguous to each other and a clean oil fountain and a dirty oil receptacle and common means for conveying clean oil to the applying roller, 90 and for removing dirty oil from the removing roller.

2. A printing press having an offset mechanism coöperating with an impression cylinder and including in combination oil applying and oil removing rollers engaging the impression cylinder closely contiguous to each other and a clean oil fountain and a dirty oil receptacle, and means for conveying clean oil to the applying roller and for 100 removing dirty oil from the removing roller, 95 said means including a common roller.

3. A printing press having an offset mechanism coöperating with an impression cylinder and including in combination a plurality of rollers operating together to apply clean oil to and to remove dirty oil from the impression cylinder, one of said rollers participating in both said actions.

4. A printing press having an offset mechanism coöperating with an impression cylinder and including in combination a plurality of rollers operating together to apply clean oil to and to remove dirty oil from the impression cylinder, one of said rollers participating in both said actions and separate receptacles for clean and dirty oil.

5. A printing press having an offset mechanism coöperating with an impression cylinder and including in combination oil applying and oil removing rollers engaging with impression cylinder closely contiguous to each other and a clean oil fountain and a dirty oil receptacle, and means for conveying clean oil to the applying roller and for 120 125 130 135

- removing dirty oil from the removing roller, said means including a roller conveying clean oil on one side thereof and dirty oil on the other side thereof.
5. 6. A printing press including in combination an impression cylinder, two form cylinders coöperating therewith and both printing on the same side of the paper and nearly a semi-circumference apart, and an 10 offset mechanism including oil applying and oil removing rollers engaging the impression cylinder as a single group at one place on the cylinder, a clean oil fountain and a dirty oil receptacle and intermediate rollers 15 including a common roller.
7. In a printing press, an offset mechanism coöperating with an impression cylinder and including in combination a clean oil fountain, a fountain roller therein, a 20 reciprocating feed roller taking oil from the fountain roller, an intermediate roller receiving the oil from the feed roller, a roller receiving the oil from the intermediate roller and applying it to the impression cylinder, 25 a roller in advance of the oil applying roller running in contact with the impression cylinder but at a different surface speed, to remove the oil and dirt from the impression cylinder, said removing roller also running in contact with said intermediate roller, a conveying roller receiving the dirty oil from the intermediate roller, and a dirty oil receptacle with a roller therein receiving the dirty oil 30 from said conveying roller, and a scraper removing the dirty oil and depositing it in said receptacle.
8. In a printing press, an offset mechanism coöperating with an impression cylinder and including in combination a clean oil fountain, a fountain roller therein, a reciprocating feed roller taking oil from the fountain roller, an intermediate roller receiving the oil from the feed roller, a fabric coated roller receiving the oil from the intermediate roller and applying it to the impression cylinder, a fabric coated roller in advance of the oil applying roller running in contact with the impression cylinder but at a different surface speed, to remove the oil and dirt from the impression cylinder, 40 said removing roller also running in contact with said intermediate roller, a conveying roller receiving the dirty oil from the intermediate roller, and a dirty oil receptacle with a roller therein receiving the dirty oil 45 from said conveying roller, and a scraper removing the dirty oil and depositing it in said receptacle.
9. In a printing press, an offset mechanism coöperating with an impression cylinder and including in combination a clean oil fountain, a fountain roller therein, a reciprocating feed roller taking oil from the fountain roller, an intermediate roller receiving the oil from the feed roller, a roller receiving the oil from the intermediate roller and applying it to the impression cylinder, a roller in advance of the oil applying roller running in contact with the impression cylinder but at a different surface speed, to remove the oil and dirt from the impression cylinder, said removing roller also running in contact with said intermediate roller, a conveying roller receiving the dirty oil from the intermediate roller, and a dirty oil receptacle with a roller therein receiving the dirty oil 50 from said conveying roller, and a scraper removing the dirty oil and depositing it in said receptacle.
10. In a printing press, an offset mechanism coöperating with an impression cylinder and including in combination a clean oil fountain, a fountain roller therein, a reciprocating feed roller taking oil from the fountain roller, an intermediate roller receiving the oil from the feed roller, a roller receiving the oil from the intermediate roller and applying it to the impression cylinder, a roller in advance of the oil applying roller running in contact with the impression cylinder but at a different surface speed, to remove the oil and dirt from the impression cylinder, said removing roller also running in contact with said intermediate roller, a conveying roller receiving the dirty oil from the intermediate roller, and a dirty oil receptacle with a roller therein receiving the dirty oil 55 from said conveying roller, and a scraper removing the dirty oil and depositing it in said receptacle.

In testimony whereof, I have signed my name to this specification, in the presence of two subscribing witnesses.

JOSEPH J. WALSER.
